[57] **ABSTRACT**

A spacing and support bracket combination selectively lockable at a plurality of angles, comprising: a first bracket of substantially L-shaped cross section, said first bracket having a major flange and a minor flange, said major flange including means for attachment to a constructional surface, and said minor flange including means for attachment to a bracket surface at any of a plurality of relative angles; and a second bracket of substantially L-shaped cross section, said second bracket being substantially identical to said first bracket, wherein the minor flange of said second bracket is securable to the minor flange of said first bracket at any of a plurality of relative angles, said relative angles being defined by the particular angle between the planes of said major flanges of said first and second brackets, whereby any two constructional surfaces may be joined at any of said plurality of angles by the securing of said minor flanges to each other at the desired relative angle and by securing said two major flanges to adjacent constructional surfaces.

BAY WINDOW ASSEMBLY WITH ADJUSTABLE SPACING AND SUPPORT LOCK BRACKET COMBINATION

The invention described herein may be manufactured, used and licensed by Fred Reuten, Inc., a corporation of the State of New Jersey, for all corporate purposes without the payment to me of any royalty thereon.

BACKGROUND OF THE INVENTION

The present invention relates to certain constructional elements used in the building trades, and more specifically to those constructional elements utilized in the fabrication of bay window structures.

A long standing and persistent need in the field of bay window construction has been that of obtaining a proper angular displacement between the individual units of a window system. The traditional approach to this problem has been the placing of wooden wedges between adjacent jambs of the window units. The major shortcomings of this approach are (1) the time involved in cutting the wedges to size, (2) the cost, which can fluctuate greatly, of the wood for the wedges, (3) the difficulty in obtaining a high degree of accuracy in the angular dimensions of the wedges, and (4) the relatively limited strength of wedges, particularly along certain grain lines.

One proposed solution to the above-stated problem appears in the U.S. Pat. to C.K. Sitterly, No. 3,561,176 (1971) entitled "Bay Window Structure". Said patent utilizes an angled assembly jig on which the window units are placed side-by-side with adjacent edges on the inner side of the assembly jig. The inner adjacent edges are then joined by a bendable connecting strip of either metal or plastic. The outer adjacent edges are covered and connected by a thick wooden strip that imparts to the units an appearance of a continuous bay window structure.

While certain economies of time and money are evidently achieved through the Sitterly approach, these economies are achieved at the cost of a weaker over-all window structure. This is because the adjacent jambs are not joined at their lateral surfaces, but rather along their edges.

Such a joinder of surfaces has traditionally been achieved through the use of a wedge. Accordingly, the present invention can be viewed as an effort to achieve suitable substitute for the wooden wedge.

Among those constructional elements in the prior art that might be utilized as wedge substitutes, the U.S. Pat. to J. A. MacKenzie, No. 2,632,533 (1953), entitled "Constructional Element," possesses the greatest relevancy. MacKenzie discloses a two-element combination of L-shaped brackets that can readily be joined to form a right-angle wedge substitute. However, in attempting to simulate non-right angle wedges, MacKenzie is forced to utilize an additional third element, namely a gusset plate. This three-element arrangement is both cumbersome to assemble and obviously more expensive than a two-element combination would be.

Consequently, a significant need that the instant invention fulfills is the development of a two-element combination capable of simulating the function of a plurality of wedges, each having a different apex angle.

SUMMARY OF THE INVENTION

An object of the present invention is to provide a

constructional element that can function as a substitute for a wedge.

Another object is to provide a wedge equivalent wherein the apex angle of the wedge may be selectively chosen.

Yet another object is to provide a means for providing a wedge substitute that can be economically utilized in the construction of a bay window system.

A still further object is to provide a novel and economical method of assembling bay window structures.

The constructional element of the present invention comprises the combination of a first bracket of substantially L-shaped cross section, said first bracket having a major flange and a minor flange, said major flange including means for attachment to a bracket surface, and said minor flange including means for attachment to a bracket surface at any of a plurality of relative angles; and a second bracket of substantially L-shaped cross section, said second bracket being substantially identical to said first bracket, wherein the minor flange of said second bracket is securable to the minor flange of said first bracket at any of a plurality of relative angles, said relative angles being defined by the particular angle between the planes of said major flanges of said first and second brackets, whereby any two constructional surfaces may be joined at any of said plurality of angles by the securing of said minor flanges to each other at the desired relative angle and by securing said two major flanges to adjacent constructional surfaces.

The method of bay window construction of the present invention comprises the steps of arranging successive pairs of a plurality of window frame units with side-by-side adjacent jambs facing each other; the securing of a plurality of two double flanged brackets of substantially L-shaped cross section to each other along their respective minor flanges such that the major flanges of said brackets are oppositely directed and further such that the planes of said major flanges intersect to form a particular relative angle; securing said major flanges to said respectively opposite side-by-side adjacent jambs of said window frame units, thereby forming a bay window structure wherein each adjacent window frame unit is angularly displaced from its adjacent unit by the particular relative angle at which the planes of said major flanges have been secured.

BRIEF DESCRIPTION OF THE DRAWINGS

FIG. 1 is a front perspective view of a three-unit bay window.

FIG. 2 is a horizontal cross-sectional view of FIG. 1.

FIG. 3 is an enlarged horizontal sectional view taken substantially along line 3—3 of FIG. 1, illustrating a 30 degree constructional element secured to adjacent window jambs.

FIG. 4 is a perspective view of a first bracket.

FIG. 5 is a perspective view of a complementary second bracket.

FIG. 6 is a perspective view of the present constructional elements secured at a 45 degree angle.

DETAILED DESCRIPTION OF THE INVENTION

The present invention utilizes two substantially identical brackets 10 and 12 (see FIGS. 3 and 4). Each of these brackets are substantially L-shaped in cross section and consists of a major flange and a minor flange. The major flange of bracket 10 is denoted as element 14; the minor flange as element 16. Similarly, the major

flange of bracket 12 is denoted as element 18; the minor flange as element 20.

The major flange of each bracket includes a means for attachment to a constructional surface. The particular means illustrated in FIGS. 4 and 5 is a plurality of holes 22 through which screws or nails can easily be driven. Alternate means of attachment, for example, by gluing, would be equally suitable.

Each of the minor flanges 16 and 20 exhibits a means for mutual attachment at any of a plurality of mutual angles, wherein a mutual angle 24 is defined by the angle of intersection of the planes of the major flanges 14 and 18 (see FIG. 6). The means illustrated in FIGS. 4 and 5 comprises a plurality of lines of colinear holes; each of said lines lies at a predetermined angle 26 with respect to the line of intersection of the major and minor flanges (see FIG. 4). This predetermined angle 26 is always one-half of the desired mutual angle 24. This technique enables bracket combinations of any number of angles to be readily formed simply by providing lines of holes at the proper predetermined angles. The brackets then can be easily joined as by rivets 28 (see FIG. 6).

It is to be noted that other means for obtaining a plurality of mutual angles would be equally suitable. One such means would comprise the use of a series of concentric curved slots emanating from the point 29 which is the intersection of the planes of the major flanges 14 and 18.

Whether using holes or slots, a substantially triangular shape is best suited in designing the minor flange.

After the brackets have been mutually secured, they are ready to be placed between adjacent units 31 of a bay window structure (see FIGS. 1 and 2). The mutual angle 24 at which the brackets have been joined will, as aforesaid, determine the angle between the planes of the units 31. In order to join the units, the major flanges 14 and 18 are joined to the window jambs 32 and 34 as by screws 36 (see FIGS. 2 and 3).

The enlarged cross-sectional view of FIG. 3 illustrates the manner in which the present invention serves as a wedge substitute: both the cross-sectional configuration and the vertical and horizontal lines of force are fully simulated. Consequently, it is seen that an effective wedge substitute can be obtained without the investment of time, labor and money that wedges have heretofore required. Also, the simplicity of the present invention should be noted: In terms of manufacturing, the forming of the brackets is a matter of stamping and bending standard sheet steel stock. In terms of assembly, a laborer need only squeeze two rivets into a selected set of lines of holes in the minor flanges, and the wedge substitute, at the desired apex angle, is ready for installation.

It is thus seen that the objects set forth in the Summary of the Invention are among those made apparent from, and efficiently attained by, the constructional el-

ement of the preceding description.

I wish it to be understood that I do not desire to be limited to the exact detail of construction for obvious modification will occur to persons skilled in the art.

Having thus described my invention, what I claim as new, useful and non-obvious, and with this instrument secure by Letters Patent of the United States is:

1. A bay window structure including a spacing and support bracket combination selectively lockable at a plurality of angles, comprising:

a. a first bracket of substantially L-shaped cross section, said first bracket having a major flange and a minor flange, said major flange including means for attachment to a constructional surface, and said minor flange including a plurality of lines of colinear holes, each of said lines lying at a different angle with respect to the line of intersection of said major and minor flanges;

b. a second bracket of substantially L-shaped cross section, said second bracket being substantially identical to said first bracket, wherein the minor flange of said second bracket is securable to the minor flange of said first bracket at any of a plurality of relative angles, a relative angle being defined by the angle between the planes of said major flanges of said first and second brackets, and in which said first and second brackets are joined by the securing together of their said minor flanges along angularly corresponding pairs of said lines of colinear holes, whereby any two constructional surfaces may be joined at any of said plurality of angles by the securing of said minor flanges to each other at the desired relative angle and by securing said two major flanges to adjacent constructional surfaces; and

c. a plurality of window frame units arranged with side-by-side adjacent jambs facing each other, wherein said edges are mutually secured and angularly arranged through the use of a plurality of said bracket combinations, thereby forming a window structure.

2. The combination as recited in claim 1 in which said combination further includes a plurality of window units having flat outer constructional surfaces, wherein said units are mutually secured at desired relative angles along said outer surfaces through the use of a plurality of said bracket combinations, thereby forming a window structure.

3. The combination as recited in claim 2 in which the plane of said minor flanges is perpendicular to the planes of each of two adjacent constructional surfaces.

4. The combination as recited in claim 3 in which said minor flanges are mutually secured to each other by rivets.

5. The combination as recited in claim 4 in which said brackets are formed of steel.
